EMILIO STANSFIELD, OF BERGAMO, AND EMILIO BRUNNER, OF MILAN, ITALY

DRAWING FRAME

Application filed February 19, 1929, Serial No. 341,198, and in Italy March 1, 1928.

The present invention relates to a drawing frame with a great number of cylinder pairs, applicable to speed frames, ring spinning frames and self-acting mules for the spinning of cotton and other textile fibres of similar nature.

In the accompanying drawings:

Fig. 1 is a diagram of a drawing frame with six cylinder pairs;

10 Fig. 2 shows the actual application of the drawing frame to a spinning frame;

Fig. 3 shows the drawing frame with eight cylinder pairs;

15 Figs. 4 and 5 show drawing frames with 5 or 7 pairs.

The drawing frame according to Figs. 1 and 2 comprises four pairs of cylinders, which may be called drawing pairs proper, and two pairs of small cylinders which we shall call 20 auxiliary pairs.

The cylinder pairs A—A', B—B', C—C', D—D', are the drawing pairs proper.

The pairs a—a' and b—b' are the auxiliary pairs.

25 The form of invention shown in Figs. 1 and 2 consists of a drawing frame comprising six cylinder pairs, of which the pair D—D' is the feed pair to which the roving or slubbing is fed first; the pair C—C' has a peripheral speed slightly in excess of that of the cylinders D—D' (draught 1,05 to 1,20). The small drawing out that takes place between these two pairs is effected under abnormal reach 30 conditions inasmuch as the distance between the tangency lines of the two pairs is much greater than the length of the longest fibres, instead of being held between the limits corresponding to the longest fibres of the cotton to be dealt with (in the case of Fig. 2 the reach is 55 mm.). The scanty drawing out performed between the two said pairs serves as a preliminary drawing, preparatory to the drawing proper carried out by the two following pairs, inasmuch as the said preliminary drawing removes to a large extent the noxious influence of the twist necessarily present in the roving or slubbing fed into the drawing frame. The accompanying figures 45

50 show a fixed, invariable reach between the

cylinder pairs D—D' and C—C'. This 55 mm. reach may be used in connection with the following cottons without distinction: Egyptian 38 mm. cotton (Sakellaridis), Egyptian 32 mm. cotton (Ashmouni), American 32 mm. 60 cotton, and 24 to 28 mm. American cottons. If desired, however, the machine may be so constructed that this reach may be varied, and the said cylinder pairs should then be made independent and adjustable.

After the small preliminary drawing between D—D' and C—C' the drawing proper is effected, this being divided in two stages namely:

(a) First stage between B—B' and C—C'; this is the smaller drawing of the two and may vary from 2 to 8;

(b) Second stage between A—A' and B—B'; this is a greater drawing and may be as great as 20 and even 25.

In order to fix the meaning of the term "drawing" or "draught", when we say that the draught between A—A' is 20 we mean that the peripheral velocity of the cylinders A—A' is 20 times that of the cylinders B—B'.

The novelty of our drawing frame lies just in the subdivision of the drawing under the special conditions indicated in the accompanying figures, viz. with the assistance of two pairs of small cylinders a—a' and b—b'.

The small cylinders b—b' are inserted between the pairs B—B' and C—C'; we call them auxiliary cylinders, because actually the drawing takes place only between the pairs B—B' and C—C'.

The small cylinders b—b' are revolving at the same speed as the cylinders C—C' and their duty only is to withhold the shorter fibres while the longer ones slide under the small pressure-cylinder owing to the pulling action exerted on them by the cylinder pairs B—B'.

We wish to recall that when a cotton is classified as a 32 to 38 mm. cotton these figures represent the length of the longer fibres in the lot; the large majority of the fibres, however, has a smaller length varying from 15 to 32 mm.

In order that the drawing may be regularly effected between two cylinder pairs it is re-

quired that all fibres, whether short or long, shall preserve the velocity imparted to them by the feed cylinders up to the moment that their forward end is gripped by the cylinders revolving at a greater velocity.

6 The fulfilment of this essential condition is secured in our drawing frame, both for the drawing taking place between the pairs A—A' and B—B' and for the drawing occurring between the pairs B—B' and C—C', by the fact that between the said pairs the small cylinders a—a' and b—b' are inserted.

10 The reach between the pairs A—A' and B—B' as well as between the pairs B—B' and C—C' must of course be designed to suit the length of the longer fibres, that is, the reach should be slightly greater than the length of the longest fibres.

15 The reach between A—A' and a—a'— as well as between B—B' and b—b', on the contrary, must be designed as small as possible as clearly indicated on our drawings.

20 Of course the pressure exerted by the small pressure-cylinders a—a'— and b—b'— must be such that the longer fibres on which the pulling action of the cylinders A—A' or B—B' is already exerted may slide under the said small cylinders, and that at the same time the shorter fibres may preserve their 25 reach up to the moment they too are gripped by the cylinders A—A' or B—B'.

25 A great importance attaches to the weight of the small pressure-cylinders a—a'— and b—b'—. Their weight is closely bound to the 30 distance between the tangency lines A—A' and a—a'—, B—B' and b—b'—.

35 If this distance is as small as feasible, the amount of sliding will be smaller for the shorter fibres and greater for the longer fibres. Referring to the distance of 20 mm. as per Fig. 2 and to a Sakellaridis cotton of 38 mm., the amount of sliding will of course be 18 mm.; with American cotton of 30 mm. on the contrary the amount of sliding would 40 be reduced to 10 mm. only. It follows that, the reach between the pairs A—A' and a—a'—, or B—B' and b—b'— remaining unaltered, the weight of the small pressure-cylinders a—a'— and b—b'— must be smaller according 45 as the amount of sliding is smaller. To quote a practical example, in the case of 38 mm. Sakellaridis cotton excellent results are obtained with the following dimensions.

50 Cylinder a': iron, hollow, 16 mm. dia., 90 gr. weight; cylinder b': iron, solid, 12 mm. dia., 90 gr. weight; reach between 1st and 3rd cylinder pair: 45 mm.; reach between 3rd and 5th cylinder pair: 48 mm.; and by fitting on the fifth fluted cylinder a pressure-cylinder the particulars of which are: iron, hollow, 20 mm. dia., 75 gr.

55 If one and the same set of spinning machines, continuous or intermittent, has to alternately work on cottons of 32, 28 and 25 mm. staple, we suggest that the plant should

be equipped with three different sets of small cylinders, in order to change the small cylinders when changing over from one kind of cotton to the other.

It is also very important that the diameter 70 of the pressure cylinders a' and b' should be a maximum; in order to obtain the various weights, one should therefore resort to different metals or to hollow cylinders.

The novelty of our special drawing frame 75 accordingly consists in the use of three consecutive draughts, the 1st one being a preliminary or preparatory draught, whereas the 2nd and the 3rd are draughts proper and are carried out under the most favourable 80 conditions, viz. with the assistance of the small auxiliary cylinders.

If the 1st draught is 1.15, the 2nd 4 and the 3rd 15, the total draught will be:

$$1.15 \times 4 \times 15 = 69.$$

85

In this manner, very high draughts can be obtained and it is quite natural that the result should be quite satisfactory because in the case just named 69 draught is obtained, 90 not in a single stage, but in three consecutive stages.

The drawings attached to the present application illustrate an example of our drawing frame.

95

For speed frames and self-acting the drawing frame should of course be horizontal instead of inclined.

Figs. 1 and 2 are indicated with:

A, B, C, D, iron cylinders with longitudinal fluting.

a, b, small iron cylinders with longitudinal fluting.

A', B', cylinders with bushes lined with wool cloth or leather, positively pressed against the underlying fluted cylinders A or B.

C', smooth cylinder like the foregoing ones, but much larger in diameter and acting on the underlying cylinder by its weight alone.

a', b', small auxiliary pressure-cylinders, 110 they may be smooth, with longitudinal fluting, flexible, or with small peripheral grooves.

The reach between A—A' and a—a' and B—B', b—b', C—C' and c—c' is fixed.

The reach between a—a' and B—B', b—b' and C—C' is adjustable.

Referring to the drawing frame with eight pairs of cylinders, the only difference consists in the insertion of a third pair of small auxiliary cylinders c—c' (Fig. 3).

In this manner the draught is divided into four well distinct stages, viz.:

(1) Preliminary or preparatory draught between E—E' and D—D'.

(2) Draught between D—D' and C—C'.

(3) Draught between C—C' and B—B'.

(4) Draught between B—B' and A—A'.

The second, third, and fourth draughts are obtained with the assistance of the pairs of small cylinders c—c', b—b', a—a'.

130

Of course, also drawing frames having 5 or 7 cylinder pairs may be constructed, as shown in Figs. 4 and 5.

Drawing frames with more than 8 cylinder pairs may likewise be constructed (for instance with 9 to 12 pairs). We consider it unnecessary to describe them, since it is only the question of adding further drawing cylinders along the corresponding small auxiliary cylinders.

Having now particularly described and ascertained the nature of our said invention and in what manner the same is to be performed, we declare that what we claim is:—

- 15 A cotton drawing machine comprising a pair of feeding rolls, a pair of drawing rolls spaced from said feeding rolls by a distance considerably greater than the fibre length of the cotton to be treated and having a peripheral speed slightly greater than said feeding rolls, other pairs of drawing rolls beyond said first pair of drawing rolls spaced from adjoining pairs of drawing rolls by distances slightly greater than the fibre 20 length of the cotton to be treated, the peripheral speeds of said pairs of drawing rolls increasing progressively, and pairs of auxiliary rolls between the adjacent pairs of drawing rolls beyond the first pair of drawing 25 rolls, the lower rolls of each of said pairs of auxiliary rolls being driven at the same peripheral speed as the preceding pair of drawing rolls, the upper rolls of each of said pairs of auxiliary rolls being held in position against the lower rolls by gravity only, said pairs of auxiliary rolls being closely adjacent to the succeeding pairs of drawing 30 rolls.

Signed at Milan (Italy), this 31st day of January, 1929.

EMILIO STANSFIELD.
EMILIO BRUNNER.
